UNITED STATES PATENT OFFICE

GEORGE PFLEEEGER, OF DEERFIELD, NEW YORK.

IMPROVEMENT IN FIRE-ESCAPE LADDERS.

Specification forming part of Letters Patent No. 143,462, dated October 7, 1873; application filed May 6, 1873.

To all whom it may concern:

Be it known that I, GEORGE PFLEEEGER, of Deerfield, in the county of Oneida and State of New York, have invented an Improvement in Fire-Escapes, of which the following is a specification:

Figure 1 is an end elevation of a fire-escape ladder containing my improvement; Fig. 2, a horizontal section on the plane of the lines *c c*, Fig. 1.

Similar letters of reference indicate corresponding parts in the figures.

The invention consists in a new arrangement of ratchets and detaining devices for securing an extension-ladder in any suitable position.

In the accompanying drawing, the letter *A* represents the bed or body of the carriage, mounted on wheels *B B*, and supporting a platform, *D*, that is connected by a bolt with the carriage. *E* is a crank-shaft, hung in arms *a* that project from the frame *D*, and carries a drum, *b*, between said arms, a ratchet-wheel, *d*, near said drum, and a wheel or disk, *e*, near said ratchet-wheel. *F* is an extension-ladder, made in sections. The lower section *f* is pivoted to the shaft *E*, while the other sections, *g h*, can slide along *f* to extend or contract, as desired. A rope, *i*, connects at one end to the drum *b*, passes thence upward around a friction-roller that hangs in the outer part of the section *f*, and thence to the lower part of *g*. By this rope the ladder can be extended or contracted when the drum *b* is turned. The upper sections *g* and *h* are similarly connected. A toothed segment, *m*, is formed at the lower part of the section *f*, and is in gear with a pinion, *n*, that is mounted upon a crank-shaft, *G*, that hangs in front of the frame *D*. By

turning the shaft *G*, and thereby the toothed segment, the ladder will be inclined more or less by suitable means.

By turning the crank-shaft *E*, the drum will be revolved to extend or contract the ladder in the desired manner. When contracted and placed horizontally, as shown, the ladder is in a convenient position for transportation, together with the carriage.

A click or pawl, *o*, bears against the ratchet-wheel *d*, and serves to retain the extended ladder in any position to which it may have been extended.

When it is desired to contract the ladder, the click or pawl *o* must be withdrawn from contact with the ratchet-wheel, and it is then placed against the disk *e*, where it will serve as a sort of brake to lessen the speed of the descent of the contracting ladder.

A ratchet-wheel, *p*, is also mounted upon the shaft *G*, and engages with a pawl, *q*, for the purpose of allowing the ladder to be placed at the desired inclination, and a disk similar to *E* may be employed upon *G* to receive the pawl *q*, when the contact between *p* and *q* is interrupted, for the purpose of bringing the ladder back to a horizontal position.

I claim as my invention, and desire to secure by Letters Patent—

In a fire-escape, constructed as set forth, the combination of the click or pawl *o* with the ratchet-wheel *d* and disk *e*, to operate in combination with each other, substantially as described.

GEORGE PFLEEEGER.
